(57) **CLAIM**

The ornamental design for a toy, as shown and described.

DESCRIPTION

FIG. 1 is a front, left and top perspective view of a toy, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion "9" shown in FIG. 1; and,

FIG. 10 is an enlarged view of portion "10" shown in FIG. 2.

The evenly broken lines shown in the drawings illustrate portions of the toy that form no part of the claimed design. The dot-dash broken lines around the enlargement indicia in FIGS. 1, 2, 9, and 10 are shown for the purpose of illustrating the bounds of the enlargements and form no part of the claimed design.
